DEPARTMENT STORES, INC., OF PITTSBURGH, PENNSYLVANIA, A CORPORATION
OF PENNSYLVANIA

VERTICAL CORNER ILLUMINATING MEANS

Application filed October 8, 1930. Serial No. 487,255.

This invention refers to improvements in means for illumination, particularly the interior of buildings such as stores, and is of the type generally known as concealed lighting.

The object in view is to so arrange the illuminating elements in series of vertical sections for transmission of the light through transparent or translucent covering material.

10 As illustrated, the invention is applied to the hollow corner portions of rectangular supporting columns or posts, but is applicable to any similar corner construction, either single or plural, as may be preferred.

15 The lighting element, as a lamp, is arranged at the upper end of a vertical corner space, for projection of the light rays downwardly through the vertical corner cavity within and behind appropriate cornice members of the architecture whereby the confined area of the cavity is utilized for diffusion of light rays through a series of removable corner panels of glass for lateral illumination of an adjacent space.

25 The invention is capable of various arrangements and modifications as to design and incorporation with either pre-existing or specially designed architectural embodiments in corner or column form. The construction here illustrated is in the manner above suggested, and in connection with a supporting column and laterally arranged ceiling beams, wherein the illuminating system of which the present invention forms 30 an element, is extended laterally, and which forms the subject matter of my companion application filed herewith Serial No. 487,254.

In the drawings showing one preferred utilization of the invention:

40 Fig. 1 is a perspective view of a portion of a store interior showing one of the columns in connection with the supported ceiling beams and the illuminating elements thereof;

45 Fig. 2 is an enlarged view in elevation partly in section showing the column and its association with said members;

50 Fig. 3 is a further enlarged cross section on the line III-III of Fig. 2;

Fig. 4 is a similar section on the line IV-IV of Fig. 2;

Figs. 5 and 6 are detail views in edge elevation and vertical section respectively, showing the mounting of the spring clamping means for the lower panels;

55 Fig. 7 is a detail view in elevation showing the manner of securing the upper panels.

Referring to Fig. 1, 2 represents a main ceiling area of a circumscribed rectangular or other suitable form within surrounding downwardly projecting cross beams 3 extending at right angles from the top of a supporting post or column 4.

60 Such column is substantially rectangular in cross section at its base, composed of any suitable interior weight-supporting elements, surrounded by flat or otherwise shaped panels, and with the upper portion of the column designed and constructed 65 whereby to provide for the mounting therein of the removable panels 5a and 5b which cover and enclose the interior vertical well or cavity 6.

70 Such cavity is of any suitable construction 75 having a maximum cross sectional area at its upper portion for a certain distance downwardly and then off-set, as at 7, reducing the cross sectional area of the cavity at 80 its lower portion, as in Figs. 3 and 4 respectively.

The vertical cavities 6 communicate at their upper portions with corresponding longitudinally laterally extended cavities within 85 and behind the cornice construction of ceiling beams 3, which are provided with a plurality of lamps behind the series of horizontally arranged panels 5c, as more fully described in the application above referred 90 to.

The column 4, above its main generally rectangular base portion, is surrounded with a series of flat panels extending upwardly throughout the middle portion of the column, between the corners, and terminating by edges 8, such edges being, in the construction shown, separated at a minor and maximum distance apart, for reception between them of the comparatively narrow 100

and wide sections 5b and 5a respectively, of the transparent or translucent panels.

The upper panels 5a of greatest width, adjacent the source of light A, are of angular form as in Fig. 3, consisting of a single piece of glass or other suitable transparent or translucent material, preferably in two or more sections, and fixedly mounted between the edges 8, so as to effect continuations of the right angle corner portions of the column with any suitable variations as to design within the province of the builder or architect.

As shown in Fig. 1 the uppermost panel 5a effects an angular joint with the innermost one of the laterally extending panels 5c of the ceiling beams, such uppermost panel resting by its lower edge against the upper edge of the next lowermost panel.

20 For the purpose of providing a framing or mounting of such panels I utilize a U-shaped strip 9 mounted against the adjacent edge 8 of the main wall construction, and secured by screw 10 to an inner flange 25 11, forming an extension of an inner sheet metal lining member 12 which is held in place by any suitable means, as screws 13.

The edge portions of panel 5a are cut out or notched as indicated at 14 for clearance of screw 10, by which construction the entire panel with its framing 9 may be bodily removed for cleaning or replacement by loosening the several screws.

Lowermost panels 5b are mounted in a somewhat similar manner, between the side walls 15 of a U-shaped receiving groove of sheet metal construction, at the opposite side portions of cavity 6, inwardly beyond or corresponding with the terminal edges 8. 20 For the purpose of providing for retention of the upper panels 5b in their supporting frames I utilize at each side outwardly pressing spring clamping devices 16 formed of spring tongues secured against the back middle portion of the groove by a rivet 17 or in any other suitable manner. Such spring elements project outwardly at their middle and are free at their opposite end, capable of being pressed backwardly when 25 the panel is inserted, as indicated in full lines in Fig. 4.

When it is desired to remove a panel, either edge may be pressed against the spring, thereby allowing the opposite edge 30 to be released from the frame so that the panel may be withdrawn, as indicated in dotted lines in said figure. By such means, the uppermost panel may be first removed and thereafter the next one or more lower panels may be also removed in the same manner for cleaning, replacement or any other purpose.

The uppermost panel, as shown, makes an abutting or beveled engagement against 35 the inner edge portions of the horizontal

panels 5c of the beam series, thereby effecting a continuation of the several series when completely installed. The illumination through the several vertical panels of the column, due to the confining walls of the vertical cavity or cavities, utilizing the full light values, provides a soft, pleasing and artistic effect greatly enhancing the architectural beauty of the column itself, especially when used with suitable paneling as black marble, etc.

The effect as a whole is highly artistic while providing for continued efficiency, easy and rapid removal or replacement, and continuous effective functioning.

What I claim is:—

1. Corner illumination construction for a rectangular column or the like provided with an uppermost source of light and divergently disposed panel members at each side of a vertical light cavity and communicating with said source of light, a box-shaped inner lining wall enclosing the cavity at the rear, vertical holding channels 85 mounted on the edges of said wall along the inner edge of each panel member, and angle shaped translucent light emission panels mounted therein.

2. Corner illumination construction for a rectangular column or the like provided with an uppermost source of light and divergently disposed panel members at each side of a vertical light cavity and communicating with said source of light, said cavity 100 and said panel members being of a maximum and minimum parallel sided width, a transverse back wall for the cavity, vertical holding channels mounted on the edges of the back wall, along the inner edge of each panel member, springs in said channels, and a series of angle shaped translucent light emission panels mounted in said channels by their opposite edges.

3. Corner illumination construction for a rectangular column or the like provided with an uppermost source of light and divergently disposed panel members at each side of a vertical light cavity and communicating with said source of light, vertical 110 supporting flanges mounted along the inner edge of each panel member, unit holding channels and securing screws attaching them to said flanges, and angle shaped translucent light emission panel units mounted in 115 said channels having clearance openings for the screws.

4. Corner illumination construction for a rectangular column or the like provided with an uppermost source of light and divergently disposed panel members at each side of a vertical light cavity and communicating with said source of light, vertical 125 supporting flanges mounted along the inner edge of each panel member, unit holding 130

channels and securing screws attaching them to said flanges, a leaf spring secured to the bottom of one of said channels, and angle shaped translucent panel units mounted in 5 said channels.

5. Corner illumination construction for a rectangular column or the like provided with an uppermost source of light and divergently disposed panel members the edges 10 of which terminate at each side of a vertical light cavity communicating with said source of light, an inner sheet metal back wall extending across from the opposite sides of the cavity, vertical holding channels secured 15 to the edges of the sheet metal back at the inner edges of the panel members, and angle shaped translucent panels mounted therein.

6. Corner illumination construction for a rectangular column or the like provided 20 with an uppermost source of light and divergently disposed panel members the edges of which terminate at each side of a vertical light cavity communicating with said source of light, said cavity being of a uniform parallel sided width at its upper portion and 25 of a lesser parallel sided width at its lower portion, inner back walls extending from the opposite sides of the plural width cavities, vertical holding channels secured to the 30 edges of the back walls at the inner edges of the panel members, and angle shaped translucent panels mounted in the holding channels.

7. Corner illumination construction for a rectangular column or the like provided 35 with an uppermost source of light and divergently disposed panel members the edges of which terminate at each side of a vertical light cavity communicating with said source of light, said cavity being of a uniform parallel sided width at its upper portion and of a lesser parallel sided width at its 40 lower portion, inner back walls extending from the opposite sides of the plural width cavities provided at each edge with vertical holding channels located adjacent the inner edges of the panel members, and angle shaped translucent panels mounted in the 45 holding channels.

50 8. Corner illumination construction for a rectangular column or the like provided with an uppermost source of light and divergently disposed panel members the 55 edges of which terminate at each side of a vertical light cavity communicating with said source of light, said cavity being of a uniform parallel sided width at its upper portion and of a lesser parallel sided width at its 60 lower portion, inner back walls extending from the opposite sides of the plural width cavities provided at each edge with vertical holding channels located adjacent the inner edges of the panel members, 65 compressible springs mounted in the 70

channels, and angle shaped translucent panels removably mounted in the holding channels adapted to be pressed against a spring at one side to effect withdrawal and release of the opposite edge of the panel. 70

In testimony whereof I hereunto affix my signature.

KENNETH R. CRUMPTON.
